UNITED STATES PATENT OFFICE.

ROBERT H. MOORE, OF NEW YORK, N. Y.

BOOKMARK.

Application filed February 17, 1927. Serial No. 169,023.

This invention relates to book marks, and particularly to the type which is interchangeable, as distinguished from book marks which are permanently attached to or form part of the book itself.

The principal object of the invention is to provide an efficient and improved interchangeable book mark, which will in no way interfere with the using, storage, or shelving of the book, will in no way injure or mar the book or the furniture upon which the book may be placed, will properly adapt itself to the efficient marking of any part of the book, and which will have means for identification of the book mark or of the book with which it is used.

Other objects and advantages will herein-after appear.

In the accompanying drawings,—

Fig. 1 shows a front elevation of the book mark.

Fig. 2 is a side elevation of the book mark shown in Fig. 1.

Fig. 3 shows in perspective a rear view of a book, in connection with which the book mark is utilized.

Fig. 4 shows a cross sectional elevation of the book and book mark shown in Fig. 3.

The book mark comprises a ribbon or double-cord 1 which is tied to a holder 2 in the manner shown. Said holder consists of a single piece of wire 3 of metal or any other suitable material, which is bent or configurated to form an eye 4 to which the cord 1 is tied, and from said eye diverge a pair of legs 5 in the manner shown. The ends 6 of the legs 5 are curved toward each other, as illustrated. Between the eye 4 and the legs 5 is formed a double stem portion 7, part of which together with said eye are bent obliquely to the plane in which the legs 5 lie, as indicated. Preferably, a loop 8 is formed out of the wire 3, at the intersection 9 of one of the stem-portions 7 and one of the legs 5, to which loop is secured, by means of an eyelet 10 or in any other suitable manner, an identification card 11 of paper, celluloid, or any other suitable material.

When utilizing this book mark the holder 2 thereof is inserted between the back-binding 12 and the leaves 13 of the book 14, in the manner illustrated in Figs. 3, 4, and the cords 1 may be then utilized for book marking purposes in the usual manner. While the wire 3 is here shown as of substantial thickness for convenience of illustration purposes,

the same may in actual practice be made of very thin, springy, and flexible material, whereby when the book is utilized or in closed state the holder 2 will in no way interfere with the binding, and will in no way injure or mar any portion of the book or the furniture upon which it may be placed. The inclination of the eye 4 maintains it below the edge 15 of the book cover 16, as shown in Fig. 4, thereby preventing any contact of the eye portion with anything outside of the limits of the book covers. As the legs 5 tend to spring outwardly the holder 2 is thereby firmly maintained in its place within the binding, and the curvature of its terminal 6 prevents any undue abrasion thereof against the binding. The configuration of the legs 5 and their terminals 6 are also conducive to permitting the holder 2 to tilt to any position, as shown in Fig. 3, whereby the eye 4 is permitted to assume any position along the leaves of the book to conform with any position of the cord 1 within the leaves. The oblique form of the eye 4 also serves to limit the inward placement and downward position of the holder 2 within the binding. The identification card 11 will be found convenient for writing or printing thereon the name of the owner of the book mark or of the book, or the name of the seller of the book, or any other desired information. Said card will be found particularly convenient when for any reason it is not practicable to write such information directly upon the book itself.

Variations may be resorted to within the scope of the invention, and portions of the improvements may be used without others.

Having thus described my invention, I claim:

1. A book mark having the combination of a marker cord, a wire having an eye for securing said cord thereto, and said wire having legs diverging from said eye adapted to be inserted between the back-binding and leaves of a book.

2. A book mark having the combination of a marker cord, a wire having an eye for securing said cord thereto, said wire having legs diverging from said eye adapted to be inserted between the back-binding and leaves of a book, and said eye being disposed obliquely to the plane of said legs.

3. A book mark having the combination of a marker cord, a wire having an eye for securing said cord thereto, said wire having legs diverging from said eye adapted to be

inserted between the back-binding and leaves of a book, said eye being disposed obliquely to the plane of said legs, and the ends of said legs being bent toward each other.

5. A book mark having the combination of a marker cord, a wire having a vertex portion for securing said cord thereto, and said wire having legs diverging directly from said portion adapted to be inserted between the 10 back-binding and leaves of a book.

5. A book mark having the combination of a marker cord, a wire having a vertex portion for securing said cord thereto, said wire having legs diverging from said portion 15 adapted to be inserted between the back-binding and leaves of a book, and the ends of said legs being bent toward each other.

6. A book mark having the combination of a marker cord, a wire having a vertex portion 20 for securing said cord thereto, said wire having legs diverging directly from said portion adapted to be inserted between the back-binding and leaves of a book, and said portion being disposed obliquely to the plane of said 25 legs.

7. A book mark having the combination of a marker cord, a wire having a portion for securing said cord thereto, said wire having legs diverging from said portion adapted to be 30 inserted between the back-binding and leaves of a book, said portion being disposed obliquely to the plane of said legs, and the ends of said legs being bent toward each other.

25. 8. A book identification device comprising a wire having diverging legs adapted to be

inserted between the back-binding and leaves of a book, and an identification card secured to said wire being located in a plane parallel to the plane of said legs.

9. A book identification device comprising a wire having diverging legs adapted to be inserted between the back-binding and the leaves of a book, and an identification card located between said legs being secured to 45 said wire.

10. An identification device comprising a wire having diverging legs adapted to be inserted between the back-binding and leaves of a book, said wire having a loop, and an 50 identification card located between said legs being secured to said loop.

11. A book identification device comprising a wire having diverging legs adapted to be inserted between the back-binding and 55 leaves of a book, said wire having a loop between said legs, and an identification card secured to said loop.

12. A book identification device comprising a wire adapted to be inserted between the 60 back-binding and leaves of a book, and an identification card secured to said wire.

13. A book identification device comprising a wire having diverging legs adapted to be inserted between the back-binding and 65 leaves of a book, and an identification card secured to said wire.

Signed at the city of New York, in the county of New York, and State of New York, this 15th day of February, A. D. 1927.

ROBERT H. MOORE.
